UNITED STATES PATENT OFFICE.

FRANK WILCOMB, OF NORRISTOWN, PENNSYLVANIA, ASSIGNEE TO HEMPHILL MANUFACTURING COMPANY, OF CENTRAL FALLS, RHODE ISLAND, A CORPORATION OF RHODE ISLAND.

PICK MECHANISM FOR KNITTING-MACHINES.

1,153,351.

Specification of Letters Patent. Patented Oct. 26, 1915.

Application filed January 17, 1914. Serial No. 812,734.

To all whom it may concern:

Be it known that I, FRANK WILCOMB, citizen of the United States, residing at Norristown, Pennsylvania, have invented certain new and useful Improvements in Pick Mechanism for Knitting-Machines, of which the following is a specification.

One object of my invention is to provide a pick which will operate upon short butt needles, and will have no picking action upon long butt needles.

A further object is to provide a self-contained pick and needle alining cam unit capable of being attached to or removed from the machine and embodying a swivel mounting for a single arm, double acting pick, and pressed by a spring all mounted on a bracket detachable or replaceable as one body.

Other objects of my invention will appear hereinafter.

The invention consists in the features and combination and arrangement of parts hereinafter described and particularly pointed out in the claims.

In the accompanying drawings Figure 1 is a sectional view of a needle cylinder with narrowing and widening picks associated therewith; Fig. 2 is a plan view of the widening pick unit; Fig. 3 is an elevation of the inner end of the pick unit of Fig. 2; Fig. 4 is a plan view partly in section of the widening pick and its swivel mounting; Fig. 5 is an end view of the widening pick; Fig. 6 is a bottom plan view of the widening pick; Fig. 7 is a sectional view of a needle cylinder with a widening pick unit in place showing modified controlling means for moving the pick to neutral position. It may be mentioned incidentally that the needle jack and two part needle cylinder shown in Fig. 7 are made the subject matter of another application filed by me for Letters Patent of the United States. Fig. 8 is a sectional view of another form of my pick unit; Fig. 9 is a plan view of the same; Fig. 10 is an elevation looking from the right of Fig. 9; Fig. 11 is a side view of the pick arm bracket; Fig. 12 is a plan view of the base bracket.

The narrowing and widening picks are of the same construction, one, however, being upside down in relation to the other, as shown in Fig. 1, and as I have illustrated

the widening pick in detail it will be sufficient to describe this. The head of the pick, as shown in Figs. 5 and 6, has a butt-stop or prong 1 extending down therefrom, and on each side thereof there is a laterally extending lip 2. This head is mounted upon a double acting arm 3 which is adapted to swing in first one direction and then the other to accord with the reciprocating movement of the needle cylinder. When the pick is in operative position the butt-stop 1 will be struck up by the short butt needles first on one side and then on the other, the butts in these actions assuming a position under first one lip and then the other, and as the pick arm is swung laterally, due to the revolutions of the needle cylinder and the engaged needle butt, the pick arm will be controlled to move downwardly to pick the needle, whose butt has engaged it, into operative position for widening. This control of the pick is effected by the cam member 4 having the inclines 5, along which the pick arm moves.

In order to prevent picking long butt needles should a long butt needle, for any reason strike the pick, I provide a guard at the side of the pick, and as I illustrate a double acting pick this guard will be at each side thereof. It is indicated at 6, 6, and consists in downward continuations of the side of the pick just at the rear of the flat lips 2, so that the long needle butts, if they strike the pick, will engage the guard and move the pick aside without locating themselves under the lip 2, and as the pick descends due to riding along the under side of the cam 4, the needle will not be carried down with it. In other words, in the case of the widening pick, when a long butt needle strikes the guard, it pushes it laterally, the needle continuing to travel in its normal plane. This lateral pressure on the pick forces it against the inclined edge of its cam 4 and results in a downward movement of the pick, causing it to slip out of engagement with the needle butt which proceeds in the normal plane. The guards are preferably rounded. The narrowing pick 7 also is provided with the guards just in rear of the lips which, in this instance, engage under the short needle butts, the construction of the pick head being the same in both cases excepting that the nar-

rowing pick may be said to be upside down in respect to the widening pick. The pick arm is pivoted in the fork of a post 8 which is swiveled in the bracket 9, being held in place by a washer 10 and a screw 11. The pick arm can swing vertically about its pivot, and it can swing laterally because of the swivel mounting of the post.

The pivotal mounting consists of a pin 12 passing through the pick arm and bearing in the forked post, the pick arm being secured to this pivot pin by a set screw 13. The pivot pin has an extension 14 with a shoulder at 15 bearing on the side of the post; and the outer end of this extension 14 has a disk 16 held thereto by a screw 17.

A spring 18 is coiled about the extension, one end being secured at 19 to the disk or finger piece 16, and the other end is secured 20 to a disk 20 which, in turn, is pinned at 21 to the post. The two disks 16 and 20 have flanges which afford bearings for the coil spring. This spring applies the necessary tension to the pick arm, and it will be noticed that being mounted upon the swivel post it partakes of the swiveling movement of the post, and thus always maintains its relation to the pick arm in the lateral swinging movement thereof due to contact with 25 the rotating needle butt. My invention in this respect is distinguished from constructions in which a spring is employed attached to a rigid frame part at one end and having connection with the pick arm at the 30 other end, the advantage being in my case that not only is the pick unit self-contained in that its pivoted and swivel mounting, together with the spring, are all carried as one body on the same bracket, but a practically uniform tension is applied to the 35 pick arm no matter what its position in relation to the needle cylinder may be, radial or otherwise. The spring tension may be readily adjusted by loosening the screw 17, 40 turning the finger button or disk 16 to wind or unwind the spring, and then the screw 17 is set up again to hold the disk 16 with the spring in its adjusted position.

In order to move the pick arm into neutral position, I provide a controller. This 50 may assume various forms, but in the particular form shown in Figs. 1, 2 and 3 it consists of a loop or open frame 22 through which the pick arm passes, this frame being 55 carried by a stem 23 passing down through an opening in the bracket 9 and pressed by a spring 24 which bears on a collar 25 carried by the stem and upon a shoulder or plate 26 in the bracket arm. The spring 60 being stronger than the coiled pick spring tends to force the controller downwardly to make the pick arm assume neutral position, and the controller is elevated to throw the pick into operation by any suitable 65 means such as a lever 27 operated in any

suitable manner. It will be observed that this controller with its stem and spring is mounted in the same bracket which carries the pivotal and swivel mounting of the pick arm, and which also carries the deflecting cam 5. This bracket is attached to the frame by screws one of which is shown at 70 *x* Fig. 1 passing through its base which base is indicated in Figs. 2 and 3, and the whole pick organization may be attached 75 to or removed from the machine as one body, it not being necessary to disturb the adjustment of the spring tension of the pick, the spring, as before stated, being carried by the swivel mounting and maintaining its relation to the pick arm under all conditions. No parts need be disconnected or disturbed, it being only necessary to remove the screws holding the bracket to the machine, whereupon the whole pick organization may be removed, and in replacing it 80 it is simply necessary to attach the bracket, when the pick organization will be ready for operation, the stem 23 being thus positioned in proper relation for operation by 90 the lever 27.

The narrowing pick is controlled by a cam plate 5' having a V-shaped notch or opening against the upwardly inclined edges of which the pick arm works. This 95 cam is attached to the bracket 9', and this bracket carries the swiveled post which, in turn, carries a spring and pivot arrangement like that above described.

In Fig. 7 I show a modified form of pick 100 controller which, instead of being mounted in the bracket holding the complete pick organization, is mounted apart from the said bracket. This controller comprises an arm 22' having its upper end curved over 105 the top of the pick arm, the lower part of the said controller being attached to a rod 28 by a screw 29. This rod is slidable vertically in a way formed in the fixed frame of the machine, and is operated by 110 any suitable lever the end of which is indicated at 30. For pressing the arm normally downward, a spring 31 is located in a socket piece or sleeve 32 contained in a recess of the controller arm and bearing against the fixed 115 frame at 33. This spring bears at its lower end upon the screw 29 and constantly tends to force the controller downwardly. It will be seen in this construction that the controller is arranged on the outside of the 120 fixed frame of the machine, and separate from the pick carrying bracket.

In Fig. 7 the pick arm is shown in its neutral position. In this form the spring mounting of the pick arm is substantially 125 the same as that above described designed to secure a practically uniform tension on the pick arm instead of a varying tension due to the lateral swing of the pick arm, which, in the case where a spring is attached 130

to the pick arm and to the frame, and is not carried bodily by the swivel mounting, will cause an increase of tension when the pick arm swings from its radial position to either side.

Referring to Figs. 8 to 12, I show a unit in which the pick arm is mounted on a bracket 9' which has a depending portion 34 fitting in a base bracket 35 adapted to be screwed to the base ring of the knitting head. The base bracket is split and a clamp screw 36 draws it together about the stem 34 to hold the latter together with the pick arm bracket at different heights. The deflecting cam 4 for the pick arm furnishes a support for the alining or leveling cam 37 the function of which is substantially the same as that disclosed at E' in Letters Patent of the United States granted to J. D. Hemphill September 7, 1909, #933,443.

It will be observed that the depending portion 34 carries the stem 23 of the loop 22, together with its spring, and that the main part or the pick arm bracket carries the swivel mounting of the pick arm in addition to the deflecting cam and the leveling cam for the needle butts. By loosening the clamp screw 36 the pick arm bracket, together with the devices just mentioned, carried thereby, can be raised or lowered to suit machines with needle butts of different levels, and when the proper position is reached the tightening of the screw 36 will set the pick unit in this adjustment. By this adjustment the pick can be brought into the path of the needle butts on coarse gages and fine gages or tight or loose knitting. It will be observed also that the pick adjustment and the adjustment of the leveling cam takes place in unison.

In some cases, as in the Hemphill type of machine, the widening pick is attached to the base ring of the machine, while the narrowing pick is attached to the plate which carries the cams. When the cams are raised to make tight work or lowered to knit loose work, the narrowing pick is also raised or lowered with it, and the plane of the needle butts is thereby changed. The leveling or alining cam should be at all times low enough to draw all the butts to one level which is always as low or lower than the level reached by the butts raised by the narrowing pick. When the lifting (narrowing) pick 7 raises the needles into their inoperative high position, the needle butts are often out of line, irregular as to height due to the pick throwing some butts higher than others, or all of them too high to aline with the widening pick. The leveling cam guides the butts into an even true line in the proper position for the widening pick to engage the butts.

I claim as my invention:—

1. A pick for widening or narrowing hav-

ing a butt-stop with a lip on each side thereof for picking short butt needles, and a guard at each side of the butt-stop to be impinged upon by the long butts for deflecting the pick to avoid picking.

2. A pick having the butt-stop and lips for engaging the short butt needles, and guards in rear of and below said lips to prevent the long butt needles from being engaged by said stop and lips.

3. In combination, a single pick arm, a horizontal pivot pin for said arm, a vertically extending swiveled post carrying said horizontal pivot, a spiral spring about said horizontal pivot connected to the swiveled post at one end and to the horizontal pivot pin at its other end, said spring moving with the post and applying its force to move the pick arm vertically and with uniform tension in all positions of the swiveled post, and a pick cam to give the pick vertical movement as it swings laterally, substantially as described.

4. A pick for knitting machines having a butt-stop and a lip adjacent for picking short butt needles, and a guard for impact of long butt needles, said guard located in rear of the lip and in line with the butt-stop, and a cam for directing the pick, under said impact, out of the plane of movement of the needle butt, substantially as described.

5. In combination, a single pick arm, a horizontal pivot pin for said arm, a vertically extending swiveled post carrying said horizontal pivot, a spiral spring about said horizontal pivot connected to the swiveled post at one end and to the horizontal pivot pin at its other end, said spring moving with the post and applying its force to move the pick arm vertically and with uniform tension in all positions of the swiveled post, a pick cam to give the pick vertical movement as it swings laterally and a controller engaging the pick arm between its pivot and its free end, with connections for moving said controller and pick downwardly to inoperative position and in opposition to the lifting force of the spring, substantially as described.

6. A pick unit having a bracket to be attached to or detached from the machine, said bracket having mounted thereon a swivel mounting with a pick arm and its spring mounted on the swivel, a deflecting cam at the inner end of the bracket, and a controller to engage the pick arm intermediate of its pivot and its free end to move it to neutral position, and a spring mounted in the bracket and operating upon the controller, substantially as described.

7. A pick unit comprising a pick arm, a pick bracket, a pivot and swivel mounting on the bracket for the pick arm, a spring carried by the swivel mounting, and a base

- bracket in which the pick bracket is mounted adjustably to be set in different vertical positions said base bracket being detachable from the machine.
5. 8. A pick unit comprising a pick arm, a pick bracket on which the arm is mounted, a deflecting cam mounted on the bracket, said pick bracket having a depending portion, a controller for the pick arm, a stem and
- 10 spring therefor mounted in the depending portion of the pick bracket, and a base bracket in which said depending portion is adjustably mounted to be set in different vertical positions, substantially as described.
15. 9. In combination a pick bracket, a pick arm mounted thereon, a deflecting cam also mounted thereon, a leveling cam for the needle butts mounted on the face of the deflecting cam, and a base bracket in which
- 20 the pick bracket is mounted adjustably to be set at different levels, substantially as described.
10. A pick unit comprising a pick arm, a deflecting cam, a leveling cam for the needle butts, a pick bracket carrying the pick, the deflecting cam and the leveling cam, and a base bracket in which the said pick bracket is vertically adjustable, substantially as described. 25
11. In combination a pick arm, a swivel mounting for the pick arm, a spring on the swivel mounting tending to move the arm vertically, a deflecting cam for the pick arm, and a leveling cam for the needles, and a bracket carrying as a unit the pick arm, 30 its mounting, the deflecting cam and the leveling cam, substantially as described. 35

In testimony whereof, I affix my signature in presence of two witnesses.

FRANK WILCOMB.
